UNITED STATES PATENT OFFICE.

GIOVANNI EMANUELE ELIA, OF PARIS, FRANCE, ASSIGNOR TO VICKERS LIMITED,
OF WESTMINSTER, ENGLAND.

ANCHOR FOR SUBMARINE MINES.

1,095,831.

Specification of Letters Patent.

Patented May 5, 1914.

Application filed November 23, 1912. Serial No. 733,119.

To all whom it may concern:

Be it known that I, GIOVANNI EMANUELE ELIA, a subject of the King of Italy, of Hotel de Crillon, Place de la Concorde, 5 Paris, in the Republic of France, gentleman, have invented certain new and useful Improvements in and Relating to Anchors for Submarine Mines, of which the following is a specification.

10 This invention has for its object an automatic anchor for submarine mines intended to permit of automatically locking the mooring winch when this anchor reaches the desired position at the bottom of the sea in 15 order to render the length of the mooring cable independent of eventual displacements of the anchor, under the influence of currents or other causes.

The accompanying drawing is a vertical 20 axial section of a submarine mine provided with the anchor in accordance with the invention.

The anchor *a* is connected with the mine *b* of any construction by a cable *c* which is 25 wound upon a winch *d* integral with the anchor, its shaft *e* which is provided at one of its ends with an operating square *f* comprising a pump brake *g* presents at its other 30 extremity a threaded portion *h* upon which a polygonal block *i* is screwed; normally this block is housed in a frame *j* provided at its upper part with a rod *k* sliding in a support *m* integral with the anchor. At its 35 lower part this frame comprises a rod *n* upon which the fixing loop *o* of the cable *p* of a lead *q* of usual construction bears; this lead is maintained in the proper position in the anchor by doors *r* which open automatically.

40 The rod *n* is integral with a plunger piston *s* which a spring *t* bearing on the bottom of a cylinder *u* constantly tends to maintain in the position represented in the drawing. In this position the lower angle 45 of the piston *s* comes flush with a perforation *v* in which a spring bolt *x* is housed. Upon the rod *n* there is fixed a tappet *y* of suitable construction located opposite a toothed ring *z* carried by one of the cheeks 50 of the winch drum *d*.

The operation is as follows: When the mine is placed in the water with its anchor the two parts of the door *r* assume the position illustrated in broken lines and the lead 55 *q* escapes from its housing and exerts a

certain amount of traction on the rod *n*. As the latter is held in place by the block *i* it remains motionless. The parts other than the lead *q* then occupy the position represented in the drawing; the anchor *a* descends under the influence of gravity and the tappet *y* being held at a suitable distance from the teeth *z* of the ring of the drum *d* the latter is able to rotate freely solely controlled by the brake *g* and the cable *c* unwinds. When the cable *c* has unwound to a certain extent, that is to say when the winch *d* has effected a certain number of rotations, the block *i* which is prevented from rotating by its frame *j* has moved 60 upon the threaded extremity *h* until it is disengaged from this frame *j*. As the rod *k* *n* is no longer supported it obeys the action of the lead *q* and descends still farther while continuing to permit of the free rotation of 65 the drum *d*. When the lead *q* touches the sea-bottom its action is no longer exerted upon the rod *k* *n* and the action of the spring *t* becoming preponderating acts upon the piston *s* and presses upward the assemblage 70 constituted by this piston and the rod *k* *n*. The tappet *y* then engages with the teeth *z* of the winch *d* thus interrupting the rotation of the latter and the unwinding of the cable *c*. Furthermore as the lower angle of 75 the piston *s* completely uncovers the orifice *v* the bolt *x* under the influence of its spring comes beneath this piston thereby efficaciously preventing any subsequent descent 80 thereof or of its rod *k* *n*. The winch *d* is 85 thus firmly locked and the length of the mooring cable *c* is limited to the length that it presented when the lead *q* touched the sea-bottom. From this moment even if the anchor *a* is displaced under the influence of 90 a current or for any other reason even if the lead *q* should exert any action upon rod *k* *n* it can no longer cause the latter to descend as it is supported by the bolt *x* in 95 such a manner that the winch *d* is locked 100 permanently and the mine remains invariably at the depth assigned to it.

This arrangement presents the advantage 105 of insuring the desired mooring depth for submarine mines notwithstanding the eventual presence of currents or eddies and it also prevents the locking action from making itself felt at the moment of placing the mine in the water when the mine and its anchor may receive more or less violent oscillations 110

arising either from the state of the sea or from the inevitable shocks imparted to the assemblage as a whole during the launching operation, so that relatively to the mine the 5 anchor necessarily occupies the position that has been assigned to it in the fitting and it is thus possible to obtain great precision in the depth of immersion of the mine, while in addition this depth is rendered independent 10 of the ground swell or of currents which may exist at the mooring point.

The invention is applicable to submarine mines of all kinds.

Having now particularly described and ascertained the nature of my said invention and in what manner the same is to be performed, I declare that what I claim is:—

1. An anchor for submarine mines, comprising a mooring winch having its cable 20 connected with the mine, locking means for directly engaging the mooring winch to lock the same against rotation, and an automatic stop for preventing said locking means from becoming operative under the oscillations of 25 the mine and its anchor when first placed in the water.

2. An anchor for submarine mines, comprising a mooring winch having its shaft provided with a threaded portion at its end, 30 a frame having an opening, a polygonal block normally housed in said opening in the frame and screwing on the threaded end of said shaft, a rod integral with said frame, a tappet carried by said rod for engaging 35 between teeth carried by the drum of the mooring winch, a piston integral with said rod, and a spring controlling said piston and tending to press the piston and rod upward to bring the tappet into the locking position. 40

3. In an anchor for submarine mines, a mooring winch, a locking device for the mooring winch, a piston forming part of said locking device, a housing for said piston, having a perforation formed therein, a spring tending to press said piston in a direction to cause the locking device to lock the mooring winch, and a safety stop for the locking device comprising a spring bolt 45 housed in the perforation of the piston housing.

4. An anchor for submarine mines, com-

prising a mooring winch, a locking device for the mooring winch, an automatic stop for normally preventing said locking device 55 from becoming operative, the said stop being actuated by the rotation of the mooring winch to release said locking device after a certain number of rotations to permit the locking device to move into locking position. 60

5. An anchor for submarine mines, having a mooring winch, a cable wound on the winch and connected with the mine, the winch having its drum provided with teeth, the shaft of said winch having a threaded 65 end portion, a vertically movable frame having an opening, a polygonal block normally housed in said opening and screwing on the end of said shaft, the said block being moved on said shaft during the rotation of the 70 winch to release the said frame, a rod connected with the lower part of said frame, a tappet carried by said rod for engaging between teeth of the drum, a weight connected by a cable with the said rod and 75 adapted to exert traction thereon, a piston connected with said rod, a spring for pressing the piston and rod upward, when the weight reaches the sea bottom, to bring the tappet into the locking position, and means 80 for maintaining the tappet in the locking position.

6. An anchor for submarine mines having a mooring winch, a cable wound on the winch and connected with the mine, a spring 85 controlled locking device having a member adapted to engage the mooring winch to lock the same against rotation, and means for preventing said locking device from becoming operative when the mine and its anchor 90 are first placed in the water, the said means being actuated by the rotation of the mooring winch to release said locking device to permit the same to move into locking position under the action of its spring. 95

In testimony whereof I have hereunto placed my hand at Southampton Buildings in the county of London England this fourteenth day of November 1912.

GIOVANNI EMANUELE ELIA.
